SERVING TRAY ATTACHMENT

Jasper W. Collins and William G. Collins,
Wichita Falls, Tex.

Application October 3, 1947, Serial No. 141,732

Term of patent 7 years

(Cl. D44—10)

To all whom it may concern:

Be it known that we Jasper W. Collins and William G. Collins, both citizens of the United States of America, residing at Wichita Falls, in the county of Wichita and State of Texas, have invented a new, original, and ornamental Design for a Serving Tray Attachment, of which the following is a specification, reference being had to the accompanying drawings, forming part thereof, the dominant features of the design reside in the parts shown in full lines.

In the accompanying drawings:

Fig. 1 is a perspective view of a serving tray attachment, looking toward the front and from above, showing our design;

Fig. 2 is a front elevational view; and

Fig. 3 is a side elevational view thereof.

We claim:

The ornamental design for a serving tray attachment, substantially as shown and described.

JASPER W. COLLINS.

WILLIAM G. COLLINS.
